UNITED STATES PATENT OFFICE.

FERDINAND F. GOTTSCHALL, OF ST. PAUL, MINNESOTA, ASSIGNOR OF ONE-HALF TO
HENRY GOTTSCHALL, OF CHICAGO, ILLINOIS.

DRAW-BAR PROTECTOR.

1,116,413.

Specification of Letters Patent. Patented Nov. 10, 1914.

Application filed December 1, 1913. Serial No. 804,006.

To all whom it may concern:

Be it known that I, FERDINAND F. GOTTSCHALL, a citizen of the United States, residing at St. Paul, in the county of Ramsey and State of Minnesota, have invented certain new and useful Improvements in Draw-Bar Protectors; and I do hereby declare the following to be a full, clear, and exact description of the invention, such as will enable others skilled in the art to which it appertains to make and use the same.

This invention is a safety attachment for car couplings, having for its object to provide an efficient device which, in the event of the breakage of a coupling, will prevent the broken part, such as the draw-bar from falling upon the track so as to derail, or endanger a moving train.

A further purpose of the invention is to provide a supplemental automatic coupling which permits of variations in movement between two coupled vehicles.

With these ends in view, the invention comprises the suspension of a vertical member from a draw-bar at each end of a car, coöperating with which member is a coupling-bar so mounted in the vertical member as to permit of vertical and lateral movements, the outer unconfined end of said coupling bar being formed to engage and lock into a similarly formed end of a co-operating coupling-bar which is adapted to be carried by another car, the movement of said coupling bars affording the means whereby said bars may be automatically brought into locking engagement when the main couplers of the cars are interlocked.

One embodiment of the invention is disclosed in the accompanying drawings, in which—

Figure 1 is a side elevation representing a safety attachment applied to a car coupling. Fig. 2 is a detail perspective view of one of the members with a coupling bar mounted therein. Fig. 3 is a vertical sectional view through a depending member showing the coupling bar cavity and a coupling bar positioned therein. Fig. 4 is a detail view of one of the coupling bars.

The auxiliary coupling comprises a vertical member or bar, suitably suspended from the ordinary draw bar of a car, and

coöperating with its depending bar, which is placed at each end of the car, is a coupling bar adapted to be carried by the depending bar having a substantially universal movement at the free unconfined end of said coupling bar. This unconfined end is so formed that it will automatically engage and couple with a similar bar carried by another car, said coupling bars coöperating to form an auxiliary coupling for cars, and act to prevent the falling upon the track of a broken draw bar or coupling with the consequent danger to the road bed and moving train.

In the preferred embodiment of the invention disclosed in the accompanying drawings, I have shown an ordinary draw bar 1, carried by a car, a portion of which is indicated at 2, having the ordinary coupling 3 supported at the end of the draw bar.

Depending from each draw bar, preferably near the end of the car, is a section of an auxiliary coupler. This coupler comprises a substantially vertical depending member 4, which is preferably slidably mounted upon the draw bar 1, although it may be securely fastened thereto, if found desirable. The depending bar 4 is provided at its upper end with a U-shaped member 5, suitably bolted at 6 to the bar 4, said member 5 serving to suspend the bar 4 from the draw bar 1. The draw bar is shown rectangular in cross section, although it may be made in any preferred form.

Preferably near the lower end of this draw bar 4 is provided a transverse opening 7. By an inspection of Fig. 3, it will be found that the opening is of unequal widths from the front wall 4^a of the bar to the rear wall 4^b thereof. The walls of this opening are preferably inclined from the rear face 4^b to the front face 4^a, and a suitable bar 8 is adapted to be placed within the opening to be carried by said depending bar 4 in a substantially horizontal plane. The bar 8 is shown as rectangular in cross section, and is preferably of the same width throughout its length. The forward end 4^c of the opening 7 is preferably of a size to permit of the passage of the bar 8 throughout, while the rear end 4^d of

the opening is of a greater width, which permits of the bar 8 to rest upon the edge of the walls of said opening 7 at 4° substantially in the form of a fulcrum having 5 a lever, the rear end 9 of the bar 8 being permitted to have vertical and lateral play with reference to the bar 4. The bar 8 is retained in position on the bar 4 by any suitable connecting means, such as a bolt 10 which prevents the forward movement of the bar 8 and its consequent disengagement from the bar 4. If desired, another bolt 11 may be placed on said bar 8 to prevent the rearward movement of said bar be- 15 yond a predetermined point with reference to the depending bar 4. In this event, it will, of course, be understood that the bolt 11 may be placed at various positions on the bar 8 by boring a series of holes in said 20 bar, whereby the bolt 11 may be placed in any one of said holes.

The forward end of the bar 8 is shown bifurcated at 12 and having flared jaws 13, the outer walls of said jaws being substantially 25 a continuation of the outer wall of the bar 8, while the inner walls 13' are inclined inwardly to the central slot 12, to form the bifurcation of the bar. This form of the jaws 13, together with the vertical 30 and lateral movements of the coupling bar 8 with reference to the depending bar 4, permits of the automatic coupling of two bars 8 through their jaws 13, when cars of different types are brought into coupled en- 35 gagement.

The protector, when placed upon cars, will permit of its coupling bars 8 of each coupling section to automatically move into coupling engagement with each other when 40 the main car couplers 3 have moved to their interlocked positions. Should the couplers, or more especially the draw bar, become broken, these supplemental couplers 8 will operate to maintain the parts in their 45 normal position and prevent the broken draw bar from moving downwardly toward the road bed and thereby preclude serious accidents when the cars are in motion.

The device herein specifically illustrated 50 is the preferred form of the invention, but it is to be understood that the invention can be embodied in other forms without departing from the proper spirit and scope as defined by the appended claims.

55 Having thus fully described my invention, what I claim as new and desire to secure by Letters Patent, is:—

1. In a device of the character described, an auxiliary coupling section adapted to be suspended from the draw-bar of a car to co-operate with a main car coupler, said auxiliary coupling section comprising a depending bar and a coupling bar loosely mounted within said depending bar, means

at one end of the coupling bar to engage 65 a like coupling bar of another auxiliary coupling section, and means whereby said coupling bar may have both longitudinal movement with relation to the depending bar, and vertical movement at one end 70 thereof with relation to said depending bar.

2. In a device of the character described, an auxiliary coupling section adapted to be suspended from the draw-bar of a car to co-operate with the main car coupler, said auxiliary section comprising a depending bar and a coupling bar loosely mounted within said depending bar, means at one end 75 of the coupling bar to engage a like coupling bar of another auxiliary coupling section, and a plurality of stops on said coupling bar to engage said depending bar and limit the longitudinal movement of the coupling bar, said depending bar having a 80 transverse opening chambered out to permit one end of the coupling bar to assume various vertical positions.

3. In a device of the character described, an auxiliary coupling section adapted to be 90 suspended from a draw-bar of a car to co-operate with a main car coupler, said auxiliary coupling section comprising a depending bar removably mounted upon a draw bar, and a coupling-bar having one end adjustably mounted within said depending bar, said coupling bar being bifurcated at the other end thereof to automatically engage 95 a like coupling bar of another auxiliary coupling section.

4. In a device of the class described, an auxiliary coupling section comprising a depending bar slidably mounted upon a draw bar and provided with a transverse opening, a coupling bar positioned within said opening for limited movement in different directions, and means for locking said coupling bar in position on said depending bar against endwise movement.

5. In a device of the class described, an auxiliary coupling section comprising a depending bar adapted to be slidably mounted upon a draw bar and provided with a transverse opening having diverging walls, a coupling bar of substantially the same cross 115 sectional area throughout its length adapted to be retained in position in said opening to permit an unconfined end thereof to assume different positions, and means at said unconfined end of the coupling bar for engaging 120 a like coupling bar of another auxiliary coupling section.

6. In a device of the class described, an auxiliary coupling section comprising a depending bar adapted to be slidably mounted 125 upon a draw bar and provided with a transverse opening having diverging walls, a coupling bar of substantially the same cross

sectional area throughout its length adapted to be retained in position in said opening to permit an unconfined end thereof to assume different positions, the unconfined end of said coupling bar being bifurcated and provided with jaws having diverging inner walls, the jaws of one coupling bar being adapted to engage and interlock with the

jaws of a like coupling bar of another auxiliary coupling section.

In testimony whereof, I affix my signature, in presence of two witnesses.

FERDINAND F. GOTTSCHALL.
